WINDOW DRAFT SHIELD

Charles A. Anderson, New Rochelle, N. Y., assignor to Gotham Pressed Steel Corporation, New York, N. Y., a corporation of New York

Application August 30, 1934, Serial No. 742,073

1 Claim. (Cl. 98-99)

My invention relates to window draft shields and has particular reference to shields or deflectors used in connection with house windows which are opened for ventilation.

5 The object of my invention is to provide a shield which can be conveniently attached to a window casing for deflecting and breaking the draft when the lower part of the window is opened for ventilation. Another object of my invention is to 10 provide a shield which can be adjusted for windows of different width. Still another object of my invention is to provide a shield which can be inclined to a varying degree for adjusting the width of the air passage between the window and 15 the shield. Other important features of my invention reside in the simplicity of its construction and arrangements for resilient clamping of the glass panels in the telescoping frame. These and other features of my invention are more fully 20 described in the accompanying specification and represented in the accompanying drawing in which—

Fig. 1 is a perspective view of my shield attached to a window, Fig. 2 is a top view of the bracket, Fig. 3 is a side view of the same, Fig. 4 is a sectional view of the bracket with the glass panel, Fig. 5 is a longitudinal sectional view of the frame with a portion of the bracket and of the panel, Fig. 6 is a partial sectional view of the 25 frame in its telescoping portion, Fig. 7 is a section taken on the line 7—7 of Fig. 6, and Fig. 8 is a detail view showing a section of the upper portion of the bracket.

My shield or ventilator consists of two panels 35 1 preferably made of glass plates overlapping each other in the middle and supported on top and bottom by telescopic rods or channels 2 and 3. The ends of the plates are held in similar channels in end brackets 4. The end channels 40 are formed by bending back the edges of the brackets and attaching angles 5 to the sides of the brackets. The edges of the channels in the brackets and in the rods 2 are bent inwardly at an angle forming resilient lips 6, shown in Fig. 4, and similar resilient lips 8, shown in Fig. 7. The 45 channels are preferably made of a thin, resilient metal. The lips 6 are cut away at the ends of the bracket channels in order to form recesses 7 for the ends of the rods 2 and 3. The top of the bracket 4 is bent over the recess 7 thereby forming a closed place for holding the ends of the rods. The channels or rods 3 are slidably fitted in the channels 2 and have rounded off edges 8' fitting in the inside curved portions of the lips 55 6 as shown in Fig. 7. With this angular shape

of the lips they are adapted to resiliently hold the glass panels by their inner edges resting against the glass. They are spaced so as to hold tightly the double thickness of the glass in the middle as shown in Fig. 7. The end portions of 5 the glass plates are held by the lips 6 in the bracket channels which are spaced closer together than the lips 8.

The brackets 4 are made narrow at the bottom and are connected by pivots or rivets 9 10 with plates 10. The latter have holes 11 for attaching them to the inner sides of the window casing 13 by screws 12. Slots 14 are provided in the brackets 4 for the screw heads. A hook 15 is formed at the upper edge of the bracket 4 engaging the upper edge of the plate 10. This edge is curved so as to facilitate the sliding movement of the hook 15 when the bracket is turned on its pivot. Lugs 16 are formed at the upper corners of the plate 10 for limiting the movement of the 20 bracket 4. In order to provide a clear space for the movement of the hook 15, the plate 10 has outwardly projecting ribs 17 which can be stamped out of the material of the plate. These 25 ribs also serve to stiffen the plate. The pivots 9 and the hooks 15 provide sufficient friction so that the bracket 4 with the channels and plates 1 can be placed into any position between the lugs 16 and will retain this position. The turning can be accomplished by merely pulling or pushing 30 the upper ends of the brackets 4.

The parts 1, 2 and 3 can be made in uniform sizes, and the complete assembly can be fitted to windows of any width within practical limits. For assembling the shield the lower channels 35 are placed first in their correct position, fitting the ends in the lower ends of the bracket channels, after the brackets have been fitted to the window casing. The glass panels are then slid between the end channels and fitted into the lower 40 channels. The upper channels are then placed in position over the glass, fitting their ends into the recesses or sockets 7. By pushing or pulling the brackets the area of the air circulation can be varied.

45 The air draft, however strong, cannot cause the glass plates to rattle, as they are securely held between the resilient lips 8 in the overlapping portions, while the ends of the plates are also clamped between the resilient lips 6 in the brackets. The clamping effect is increased by the angular shape of the lips so that they rest against the glass by the sharp corners of the edges of the metal of the channels.

55 The construction of my window shield or ven-

tilator can be modified in minor details, of course, without departing from the spirit of my invention. Certain minor details can be also omitted. For instance, the top and bottom channels, while 5 shown of a rectangular section, may be also made round or half round. The adjustment feature of the end brackets can be also omitted.

Important advantages of my shield are that it can be made chiefly of simple metal stampings 10 in standardized sizes, with glass plates also of standard sizes; it can be shipped in a disassembled condition, and can be easily assembled on windows by the purchaser. The channels 2 and 3 are made of uniform sizes, having rounded edges 15 adjacent to the glass, which facilitate their handling and improve their appearance. The angular shape of the edges on the channels 2 and 5 tend to increase their resiliency and to provide a stronger grip on the glass plates.

20 I claim as my invention:

In a window draft shield, the combination with plates adapted to be attached to the sides of a window casing, brackets pivotally connected with said plates at their lower ends, the upper ends of said plates being curved concentrically 5 with said pivots, the upper ends of said brackets being provided with hooks engaging the curved ends of said plates, lugs at the ends of said curved edges limiting the rotational movement of said brackets, stiffening ribs on said plate adapted to 10 keep the upper edge away from the wall of said casing so as to provide room for the movement of said hook, channels attached to the inner sides of said brackets, telescopic channel-shaped rods supported by their ends in said channels, and 15 glass panels slidably overlapping each other and supported by their side edges in said rods and by their end edges in said channels.

CHARLES A. ANDERSON. 20
